Primary Examiner — Thomas Johannes*Assistant Examiner* — Sean D Lough(74) *Attorney, Agent, or Firm* — King & Schickli, PLLC**CLAIM**

The ornamental design for a fan, as shown and described.

DESCRIPTION

FIG. 1 is a bottom perspective view of the fan;

FIG. 2 is a top perspective view of the fan;

FIG. 3 is a front view of the fan;

FIG. 4 is a right side view of the fan;

FIG. 5 is a rear view of the fan;

FIG. 6 is a left side view of the fan;

FIG. 7 is a top view of the fan; and,

FIG. 8 is a bottom view of the fan.

The broken line depictions form no part of the claimed design.
